CLAIM

The ornamental design for a housing for optical components, as shown and described.

DESCRIPTION

FIG. 1 shows a perspective view of a housing for optical components according to the present invention;

FIG. 2 shows a front view of the housing for optical components illustrated in FIG. 1;

FIG. 3 shows a back view of the housing for optical components illustrated in FIG. 1;

FIG. 4 shows a right side view of the housing for optical components illustrated in FIG. 1;

FIG. 5 shows a left side view of the housing for optical components illustrated in FIG. 1;

FIG. 6 shows a top view of the housing for optical components illustrated in FIG. 1; and,

FIG. 7 shows a bottom view of the housing for optical components illustrated in FIG. 1.

The broken lines show portions of the article that form no part of the claimed design.
